UNITED STATES PATENT OFFICE.

RICHARD CLARKSON, OF PHILADELPHIA, PENNSYLVANIA, ASSIGNOR TO
BRADFORD L. WILLIAMS, OF SAME PLACE.

DESIGN FOR A BUTTONHOLE-OPENER AND BUTTONER.

SPECIFICATION forming part of Design No. 31,433, dated August 22, 1899.

Application filed July 29, 1899. Serial No. 725,543. Term of patent 7 years.

To all whom it may concern:

Be it known that I, RICHARD CLARKSON, a citizen of the United States, residing at the city of Philadelphia, in the county of Philadelphia and State of Pennsylvania, have invented and produced a new and original Design for a Buttonhole-Opener and Buttoner for Collars and Cuffs, of which the following is a specification, reference being had to the accompanying drawings, forming part thereof, in which—

Figure 1 is a top or plan view of a buttonhole-opener and buttoner for collars and cuffs, showing my design; and Fig. 2 is a side elevational view thereof.

As illustrated in the drawings, the leading or material feature of the design consists in the outline or configuration of the buttonhole-opener and buttoner.

As viewed in side elevation the opener and buttoner is essentially straight or flat at the opener end *a* and rounded or upwardly curved

at the buttoner end *b*. When viewed in plan, the flat portion *a* is tapered toward its end *a'*, which end is rounded. The curved buttoner end *b* is provided with an opening or slot *b'* of irregular outline. At one side of the slot are two points or angles *b²* and *b³*, and at the other side of said slot two similar points or angles *b⁴* and *b⁵*, staggered or arranged to the right of the angles *b²* and *b³*.

Having thus described my invention, what I claim as new, and desire to secure by Letters Patent, is—

The design for a buttonhole-opener and buttoner for collars and cuffs, substantially as shown and described.

In testimony whereof I have hereunto set my signature in the presence of two subscribing witnesses.

RICHARD CLARKSON.

Witnesses:

J. WALTER DOUGLASS,
RICHARD C. MAXWELL.
